UNITED STATES PATENT OFFICE.

JOHAN S. FASTING, OF FREDERIKSBERG, NEAR COPENHAGEN, DENMARK, ASSIGNOR TO
E. L. SMITH & CO., OF NEW YORK, N. Y., A CORPORATION OF NEW JERSEY.

HIGH-SPEED GRINDING-MILL.

1,184,842.

Specification of Letters Patent.

Patented May 30, 1916.

Application filed June 5, 1914. Serial No. 843,144.

To all whom it may concern:

Be it known that I, JOHAN S. FASTING, a subject of the King of Denmark, residing in Frederiksberg, near Copenhagen, Denmark, have invented certain new and useful Improvements in High-Speed Grinding-Mills, of which the following is a specification, reference being had to the accompanying drawing, which forms a part 10 hereof.

In a co-pending application filed by the present applicant on the 5th day of June 1914, Serial No. 843,143, is shown and described an improved high speed grinding 15 mill in which rolling members are employed to crush the material and impel the same through the mill from the feed end to the discharge end.

The present invention relates generally to 20 mills of the type shown in said co-pending case and is concerned particularly with the rolling members and devices whereby said rolling members may be adjusted with respect to the wall of the mill. When the 25 grinding operation is started it will be understood that the load thrust on the prime mover is relatively great where the grinding body rests loosely within the mill. Moreover, sudden starts and stops of the movement of the rolling member with respect to the mill is apt to wear the rolling member 30 unevenly so as to lower the efficiency of operation of the complete plant. Moreover, where movement is imparted to the grinding 35 body immediately upon the rotation of the mill, it is impossible for the coarser particles of the material to move into position between the roller and the mill and hence the crushing is not highly effective 40 until after the mill has been operated for some little time.

The object of this invention is to meet 45 the difficulties pointed out above and to provide means whereby the grinding roller or rollers may be moved out of contact with the inner surface of the mill and held in such inoperative position, until the mill is brought up to a relatively high speed and sufficient material has been fed into the 50 space between the roller and the mill to engage the surface of the roller and bring about its rotation and subsequent crushing action. In accordance with the invention the shaft of the roller is provided with two 55 bearings, the inner one of which is adjust-

able vertically to permit the roller to be raised out of engagement with the surface of the mill or lowered into engagement therewith. This bearing is preferably of such a character as to permit free vertical 60 movement of the shaft therein and by this arrangement it becomes possible to place weights on the bearing and thus increase the effectiveness of the crushing roller.

Another feature of the invention incidental to the construction briefly outlined, resides in the capacity of the shaft of the roller to be given a movement of rotation independently of the movement of rotation which the grinding mill imparts to the 70 roller. In this way, the roller may be rotated positively at a speed different from the speed of rotation of the mill and the effectiveness of the crushing action thereby enhanced.

The invention will be described more particularly with reference to the accompanying drawings, in which—

Figure 1 is a view partly in horizontal section and partly in plan of a complete 80 plant embodying the present improvements. Fig. 2 is a view, partly in elevation and partly in section of the apparatus shown in Fig. 1 and illustrating particularly the mechanical device for effecting the desired 85 adjustment of the rotating shaft.

The grinding mill *a* is mounted rotatively on an actuating shaft *b* supported in bearings *c* and *d* and having fixed on its outer end a driving pulley *d* which may be rotated from any available source of power. One end of the mill *a* is provided with an opening, indicated generally at *a'* and through which the material to be crushed may be introduced into the mill through 95 any suitable structure, not illustrated. The material after being crushed is discharged at the opposite end of the mill through peripheral openings *a*², all in the usual manner. Within the mill is mounted a crushing roller *e* fixed on a shaft *f* which extends without the mill through the opening *a'* and is mounted at its free end in suitable bearings *g* of a character to permit free lateral movement of the shaft *f*. Adjacent 100 to the end wall of the mill *a* in which is formed the opening *a'* is mounted a second bearing *h* for the shaft *f* in which rest the journals *i* for the shaft *f*. These journals *i* are movable vertically in the bearings *h* so 110

as to permit the shaft *f* and roller *e* to be moved out of engagement with the surface of the mill to any desired degree.

The invention is not concerned particularly with the devices for bringing about the movement of the journals *i*, although such devices may conveniently consist of threaded lugs *i'* formed with the journals *i* and engaged by vertically disposed screws *h*⁴ journaled fixedly in the frame *h* and carrying at the lower ends bevel pinions *h'* adapted to be engaged by corresponding pinions fixed on a rotatable shaft *h*² on one end of which is carried a hand wheel *h*³. Through the rotation of the hand wheel *h*³, the screws *h*⁴ are rotated and the journals *i* raised or lowered as may be required for the positioning of the shaft *f*. The shaft *f* rests loosely on the journal *i* and is free to raise therefrom slightly, although being guided in such movement by a yoke *f'*.

It will now be evident that when the rotation of the mill is to be started, the roller *e* may be moved out of engagement with the surface of the mill and the material introduced into the mill will eventually fill the space between the roller and the wall of the mill, provided of course that the roller has been moved approximately to its normal clearance position, at which time the friction between the material and the roller will bring about the rotation of the latter and result in the material being crushed and impelled through the mill in the manner pointed out in the co-pending case referred to. The rack and pinion engagement may be such as to permit, during the normal operation of the mill, free vertical movement of the journals *i* in the bearing *h* so that the roller *e* will rest loosely on the material to be crushed.

Another feature of the present invention, incidental to the vertical movement of the journals *i* resides in the adaptability of said journals to be weighted as conditions require to assist in the crushing action of the roller *e*. In this way, it becomes unnecessary to make the roller *e* of greater dimensions to secure a more effective crushing action since the additional weight may be transmitted

to the crushing surface through the loaded journals *i*.

Still another feature is found in the provision of a pulley *k* fixed on the roller shaft *f* outside of the bearing *h*, which pulley may be driven from any available source of power and rotate the roller *e* at any desired speed, independently of the speed of rotation of the mill *a*. It will be understood that rotation of these two members at different speeds will increase the friction between the roller and the material and thus make the crushing action more effective.

Certain of the parts of the improved apparatus have been illustrated more or less conventionally in the accompanying drawing inasmuch as the invention is not to be limited to the structural details of any of such elements and the equivalents of these elements may be readily substituted by those skilled in the art.

It is believed that from the description given the gist of the invention will appear, which is the adjustability of the roller with respect to the inner wall of the mill.

75

I claim as my invention:—

In combination with a high speed grinding mill, a rotatable grinding body disposed loosely therein on the bottom of the mill, a shaft to which the grinding body is secured extending without the mill and maintained in an angular position with respect to the axis of the mill whereby the axis of the grinding body is angularly disposed to the axis of the mill and the material is impelled through the mill during the grinding, end bearings for said shaft to prevent axial movement thereof, and a separate bearing intermediate the ends of the shaft and adjustable in a vertical plane whereby the initial position of the grinding body with respect to its tangential seat on the surface of the mill may be varied.

This specification signed and witnessed this 20th day of May A. D. 1914.

JOHAN S. FASTING.
